MILK CRATE OR THE LIKE

Houston Rehrig, Pasadena, and Bud E. Sanders, North Hollywood, Calif., assignors to Rehrig Pacific Company, Los Angeles, Calif.

Continuation-in-part of design application Ser. No. 298,909, Oct. 4, 1972. This application May 30, 1973, Ser. No. 365,377

Term of patent 14 years

Int. Cl. D9—03

U.S. Cl. D9—177

FIG. 1

FIG. 2

FIG. 3

FIG. 4

FIG. 5

FIG. 1 is a perspective view of a milk crate or the like showing our new design;

FIG. 2 is a side elevation view thereof;

FIG. 3 is an end elevation view thereof;

FIG. 4 is a top plan view thereof; and

FIG. 5 is a bottom plan view thereof.

This is a continuation-in-part of our copending application Ser. No. 298,909, filed Oct. 4, 1972.

We claim:

The ornamental design for a milk crate or the like, substantially as shown and described.
